UNITED STATES PATENT OFFICE.

ARTHUR A. MERRITT, OF WORCESTER, MASSACHUSETTS, ASSIGNOR TO WILLCOX & GIBBS SEWING MACHINE CO., OF NEW YORK, N. Y., A CORPORATION OF NEW YORK.

DESIGN FOR A SEWING-MACHINE FRAME.

45,345.

Specification for Design.

Patented Mar. 3, 1914.

Application filed October 12, 1912. Serial No. 725,522. Term of patent 14 years.

To all whom it may concern:

Be it known that I, ARTHUR A. MERRITT, a citizen of the United States, residing at Worcester, in the county of Worcester, State of Massachusetts, have invented a new, original, and ornamental Design for a Sewing-Machine Frame, of which the following is a specification, reference being had to the accompanying drawings, forming part thereof.

In the drawings—Figure 1 is a front elevation; Fig. 2 is an end elevation; and Fig. 3 is a top plan view.

I claim:

The ornamental design for sewing machine frame, as shown.

In testimony whereof I have signed this specification in the presence of two subscribing witnesses.

ARTHUR A. MERRITT.

Witnesses:

W. T. SIDDALL,
S. G. PITTS.
